UNITED STATES PATENT OFFICE

FRANK STRAUB, OF LOS ANGELES, CALIFORNIA.

THERMOSTAT.

Application filed February 2, 1924, Serial No. 390,119. Renewed May 2, 1927.

This invention relates to thermostats, particularly the type used in connection with gas fired water heaters and has for its principal object the provision of an efficient, 5 quick action thermostat.

Another object of the invention is to provide a thermostat that may be disposed under a water heater where it is not apt to be damaged, and whereby it may be placed 10 in close proximity to the burner to save in the first cost of gas pipe, water pipe and connections.

Another object of the invention is to provide a thermostat which may be adjusted 15 readily from the exterior thereof.

Another object of the invention is to provide a thermostat which may be manufactured and sold separate and apart from the water heater and which is adapted to be 20 readily connected to any of the several types of water heaters.

Another object of the invention is to provide a thermostat in which the valve and valve seat are so designed that they will not 25 tend to accumulate sediment.

Another object of the invention is to provide a thermostat in which the valve is readily accessible for inspection. It will be understood in the consideration 30 of the invention that the most practical type of thermostat for gas fired water heaters is that in which the expansion and contraction of a metal tube acts through a porcelain rod and a set of levers to operate a gas controlling valve. The levers are of necessity 35 of the compound type and require a plurality of fulcrums or bearings and must also be subject to careful adjustment. It is an important object of this invention to provide 40 a thermostat having compound levers in which thermostat the fulcrum points are provided without the use of through shafts or the like penetrating the otherwise gas tight casing in which such levers are usually 45 housed.

Other objects include the provision of simplicity of design, freedom from wear, and accessibility.

Still other objects and advantages will appear hereinafter and will be better understood by virtue of the order of their occurrence.

I have illustrated by the accompanying drawings a preferred embodiment of my invention, and in said drawings,

Figure 1, is a view in vertical section of the said embodiment.

Figure 2, is a view in end elevation thereof with the end closure plate removed, and

Figure 3, is a plan view thereof.

Figure 4, is a view in section seen on a line 4—4 of Fig. 1.

More specifically, in carrying out my invention in this embodiment, I provide a gas tight casing 5, enclosing a substantially 65 cubical lever chamber 6, and a valve chamber 7, communicating with the latter through a port 8. Said port is fitted with a removable annular sharp edged valve seat 9. A valve 10 rests on said seat and is provided 70 with a depending hexagonal guide 11, whereby upon the valve being raised from its seat gas may flow from the valve chamber to the lever chamber. The latter is provided with a gas outlet 12, into which is screw threaded 75 a gas pipe 13, which is connected to the gas burner (not shown). The valve chamber is provided with a gas inlet port 14 into which is screw threaded a gas inlet pipe 15.

In the embodiment illustrated the valve 80 chamber is vertically disposed, as is also the valve seat, while the major axis of the lever chamber is horizontal. An upper wall 16 of the casing is provided with a vertical boss 17, into which is screw threaded a copper thermostat tube 18, having a closed end 18'. Within the tube a porcelain thermostat rod 19 is provided, having its lower end 19' extending into the lever chamber. A nipple 17' is pressed on the thermostat tube in abutment with the boss 17. A pipe 20, for instance, attached to the thermostat casing by said nipple can thereby provide the means whereby the thermostat is connected with a storage tank (not shown), so that the coolest 85 water in the tank will gravitate into the pipe and surround the thermostat tube.

Upon cool water coming in contact with the thermostat tube the latter will contract, thereby forcing the porcelain tube downwards. To cause the contraction to be multiplied in effect and to act on the valve to raise it from its seat, I provide levers 23 and 23'.

Lever 23 is hereinafter known as the 105 primary lever and rests on a knife-like ridge 24, which is an integral part of a circular plug 25. Said plug is fitted loosely in a vertical bore 26, leading from the exterior of the casing into the lever chamber. This 110

bore is screw threaded and therein is fitted a screw adjustment plug 27, accessible from the exterior of the casing. Gravity holds the loose plug upon the adjusting plug.

5 The lower end of the porcelain rod abuts the rear end 29 of the lever 23, which is formed with a slight concavity 30. Likewise, a depression 31 of suitable angularity is provided in the lever where it rests on the 10 loose plug. In other words, the primary lever is adapted to rock on an adjustable fulcrum, while the porcelain rod abuts its extreme end to the rear of the fulcrum. Contraction of the thermostat tube obviously results in the rear end of the primary lever being depressed a slight distance, while the forward end of the primary lever is 15 raised a greater distance.

A salient feature of my invention resides 20 in the fact that the lever 23', hereinafter known as the secondary lever is carried solely by the primary lever and by nothing else, and is fulcrumed thereon, as by a pin 32. Said pin is supported by spaced upper 25 right ears 33 integral with the primary lever. Said secondary lever parallels the primary lever and extends rearwardly in the lever chamber, while the primary lever may be said to extend forwardly.

30 The lever chamber is closed at one end by a removable closure plate 33'. Said plate being removable permits of access to the said chamber for assembly, inspection or repair, and thereby the plate may be readily 35 machined in manufacture. The plate is provided with a transverse abutment surface 34, formed in this embodiment by providing a groove 34' therein.

40 Now a short end 35 extends forwardly from the secondary lever while the long rearwardly extending end passes below and in proximity to the depending portion of the valve. The said short end of the secondary lever is arranged to abut said surface 45 whenever the primary lever is raised sufficiently.

50 In the operation of my improved thermostat contraction of the tube will result in the forward end of the primary lever being raised gradually as the tube slowly contracts by contact with cool water. The upward movement of the forward end of the primary lever results in the latter carrying the secondary lever upward while said secondary lever is resting upon the primary lever. The figures show the parts in the 55 position which they assume just before the short end of the secondary lever abuts the said abutment surface. When the right hand end of the primary lever 23 moves upwardly, the secondary lever 23' is carried bodily until its end 35 comes in contact with the abutment 34. The abutment 34 is a fixed point and holds the end 35 against movement. The force which causes turn-

ing movement of the secondary lever 23' is applied through the point 32 by the primary lever 23. The result is turning movement of the secondary lever about the abutment as a fulcrum, because abutment 34 is fixed, 70 and point 32 is the point of application of the force. It will be seen that the lever 23', and the abutment, are so disposed with regard to the valve stem-end 36, that the lever 23' abuts the valve stem practically 75 at the same time that its end 35 abuts the stop. Thus the device employs only primary leverage until immediately prior to the abutment of the lever 23' with the valve stem. The resultant action is more rapid 80 and positive than would be the case if the secondary lever were constantly against the abutment. Therefore, the free end of the secondary lever moves with relatively great 85 velocity and quickly and easily raises the valve from its seat. Upon expansion of the copper tube the action is reversed and the valve closes as readily as it opened. As a result of the action of the levers my improved thermostat is, for all practical purposes, as sensitive and efficient as the so called "snap action thermostat" and far less costly and intricate. My improved thermostat may be adjusted as desired by turning 90 the screw plug in the correct direction. 95 The act of screwing the plug inwardly, for example, forces the levers nearer to the valve, and adjustments may be made readily at any time.

It will be apparent now that I have provided a simple and quick acting thermostat 100 which may be readily adjusted and readily assembled, repaired or inspected, and in which the levers are so mounted that friction is minimized and tendency of the valve 105 and levers to become fouled or jammed, is practically obviated.

And while I have shown and described a specific embodiment of my invention, I 110 do not limit myself in the construction and arrangements of parts, and may alter same as I desire without enlarging the scope of my invention, within the appended claims.

I claim:

1. In a device of the character described, 115 a box-like casing open at one end, a removable closure for said end, a bottom wall to said casing, a screw plug in said bottom wall adjustable from the exterior of said casing, a fulcrum element seated loosely on said plug and disposed within said casing, a primary lever in said casing mounted on said fulcrum element, a thermostat rod vertically disposed with an end resting on said lever, a secondary lever fulcrumed on said primary lever, and a stop element carried by said closure disposed in the path of movement of an end of said secondary lever. 125

2. In a thermostat, a primary lever, a secondary lever carried bodily by and ful-

crumed on said secondary lever, an adjustable fulcrum for said primary lever, a fixed non-adjustable abutment member disposed to be abutted by one end of the secondary lever, a valve disposed to be abutted by the other end of the secondary lever; the levers, valve and abutment member so positioned with regard one another, when the parts are in normal position, as to cause the secondary lever to abut the valve practically immediately after it abuts the abutment member.

3. In a thermostat, a casing having a bottom wall and enclosing a gas tight space, a fulcrum member vertically adjustable

through the bottom wall, a primary lever held by gravity on said fulcrum, a vertical thermostat rod supported by said primary lever, a second lever carried bodily by and fulcrumed to said primary lever; both levers being substantially horizontally disposed and held by gravity in normal position, a vertical valve having a stem depending into the gas tight space in position to be abutted by one end of said secondary lever, and a non-adjustable abutment internally of the gas tight space adapted to be abutted by the other end of said secondary lever.

FRANK STRAUB.
